Patented May 26, 1925.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Original application filed November 18, 1918, Serial No. 262,939. Divided and this application filed May 1, 1922. Serial No. 557,630.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention is a division of my application Serial No. 262,939, filed November 18, 1918, (now Patent No. 1,425,293, dated August 8, 1922), and relates principally to typewriting machines of those of the class disclosed in the patent to Wernery and Smith, No. 1,132,055, in which superposed plies of work-web are led to the typewriter carriage from the rear and passed forwardly around the platen and upwardly to receive the type impressions. In such machines, the platen is displaceable upwardly after the completion of the typing of each form on the web, to permit the plies of web to be straightened, so that the carbon-sheets which interleave the plies may be retracted for fresh use. The typed form is then severed from the web.

In some cases, it is desired to retain in the machine a condensed record-sheet, to receive carbon impressions of a succession of bills or forms that are typed upon the main webs; the forms being usually severed from the web one by one after being typed.

An object of this invention is to improve the means for controlling the record-sheet, which usually lies next to the platen, being advanced with the web plies during line-feeding operations, but remaining stationary during the pulling forward of the web preparatory to tearing off the typed form therefrom.

As herein disclosed, the platen is automatically rotated one, two or three line-spaces during the upward displacement of the platen for permitting the webs to be straightened out. Since this platen-displacing operation occurs once for every form that is typed upon the web, it results that the record-sheet, which remains in contact with the platen, is automatically advanced thereby, independently of the plies of web, once for every form that is severed from the web. The record sheet is held against the platen by special feed-rolls, which remain effective as the platen rises, to insure the advance of the record-sheet with the platen at this time.

These rolls are preferably placed one on each end of the platen, to run upon the side margins of the record-sheet, which, for this purpose, may be made wider than the plies of web. These rolls may be placed at the front of the platen, so as to bite the record-sheet nearly at the printing line, so that about all of the record-sheet may be used, avoiding the necessity of providing excessive blank margins at either top or bottom thereof.

A feature of this invention is an improvement in the manner of mounting such rolls. They are carried upon the forward ends of arms which extend forwardly from a horizontal rod, which extends along the back of the carriage and is mounted thereon. These arms may slide along the rod to accommodate sheets of different widths. Moreover, these special rolls may be released from the platen whenever desired, this being accomplished by means of a key mounted upon the carriage and connected to release the roll-carrying arms wherever they are adjusted along the rod.

While the platen is displaced, a connection between the ordinary line-space wheel and the revoluble platen is maintained by a train of gearing, such a train being shown in said Wernery and Smith patent. As herein disclosed, the line-spacing wheels are driven automatically during the rise of the platen, and thereby revolve the same; and the usual spring detent, riding over the teeth of the line-space ratchet wheel, serves to hold the platen at the position to which it is rotated by the line-space mechanism. The line-space mechanism of the Underwood machine usually comprises a slide which carries a pawl, and said pawl engages the line-space ratchet wheel whenever the slide is pushed backwardly, this usually being accomplished by a lever or handle. As herein disclosed, the platen frame is provided with an arm which engages said slide or a pin thereon, and drives the slide rearwardly for effecting the line-space movement.

Said driving arm, which is connected to the platen frame, may be so proportioned as to effect a complete driving stroke of said pawl-carrying slide, the same as done by the usual manually-operated lever, and hence the line-spacing pawl may remain normally out of engagement with the ratchet wheel, as before, and the usual line-space regulator

may be employed which controls the duration of the engagement of the driving pawl and the ratchet wheel, and therefore controls the extent of line-spacing movement of the platen. Thus, the extent of automatic advance of the record-sheet may be regulated.

Other features and advantages will hereinafter appear.

10 In the accompanying drawings,

Figure 1 is a perspective front view of an Underwood typewriting machine illustrating the class disclosed in said Wernery and Smith patent, and showing my improvements in one form, some of the parts being in normal positions.

Figure 2 is a sectional side elevation of the carriage of said Underwood machine, showing parts in normal positions.

20 Figure 3 is a fragmentary view to illustrate the manner of releasing the rolls which hold the record-sheet upon the platen of the typewriting machine.

Figure 4 is a view showing the platen near the final stage of its upward displacement, and illustrating the manner in which the line-spacing rotating movement of the platen is begun at this stage.

Figure 5 is a view showing the parts seen in Figure 2, but illustrating the upward displacement of the platen as completed, and the line-space operation also as completed.

35 The plies of web 10 are led in at the rear of the machine, and passed forwardly over a traveling slide 11, which has blades 12 to carry sheets 13 of carbon in between the plies of web, and which may slide forwardly with the plies, and also slide rearwardly, independently of the plies, to feed the carbons 40 to fresh positions relatively to the webs. The plies with the interleaved carbons pass downwardly around the revolute platen 14 and between the same and the usual releasable bottom feed-rolls 15, and then upwardly 45 in front of the platen to a position to receive the impression of the types 16.

A separate sheet 17 is placed next to the platen and is faced with a special carbon-sheet 18 which may be carried by said slide, the special sheet receiving the carbon impressions of a succession of forms which are typed and then torn off from the web plies.

50 After the completion of the typing of a form, the platen is raised or displaced upwardly, to permit the plies to be straightened out preparatory to sliding back the carbon-carrier, Figure 5. The platen for these purposes is mounted upon a swinging frame 19, which is hinged at 20 to a main platen frame or carriage 21, so that the platen may be swung upwardly.

55 Connection between the platen and the usual line-space wheel 22 and platen-rotating knob 23 is maintained by means of a train of gearing comprising gears 24, 25,

one rigidly connected to the line-space wheel, and the other rigidly connected to the platen 14, said gears both meshing with a broad pinion 26, which is mounted upon the main platen frame concentrically with the hinge 20, so that connection between the line-space wheel and the platen is always maintained.

Upon the swinging platen frame 19 is fixed, at one end, a driving arm or tappet 27, which at the upward swinging of the platen engages a pin 28 which projects from a line-spacing slide 29 usually provided upon the Underwood typewriter. By this means, said slide is given a full rearward stroke, the same as it receives from the manually-operated lever 30. Said slide is operable either by said driving arm or said operating lever. Upon said slide 29 is the usual pawl 31 for engaging the teeth of the line-space wheel 22. Other devices are usually found upon this portion of said Underwood machine, including a stop to prevent overthrow of the pawl, and means to regulate the extent to which the line-space wheel is rotated by the pawl, said regulating means including the handle 32, which is usually adjustable to three positions for single, double and triple line-spacing. The extent of the movement of the slide 29 is the same for all three positions of the line-space regulator 32, and hence the extent to which the platen is automatically rotated at the elevation thereof may be determined by the adjustment of this regulator 32; the slide 29 being given a full stroke in every instance.

When the latch 33 is released that usually holds down the platen-swinging frame 19, and said frame is swung up, an independent regulatable rotation of the platen is automatically effected. When the platen is dropped back to printing position, the line-spacing slide 29 is returned by its usual spring 34, and the parts resume normal positions with the latch 33 resuming its function of holding down the platen frame 19.

105 This automatic line-feeding of the platen serves to advance the record-sheet 17 independently of the webs 10, the side borders of said record-sheet being held against the platen by means of special rolls 35, which escape the plies of web 10, and grip the record-sheet 17 at points near the printing line, avoiding waste of paper.

110 While other kinds of rolls 35 may be employed and while they may be otherwise placed, it is preferred to place them upon the forward ends of arms 36, which extend forwardly over the top of the platen and are carried upon a horizontal rod 37 which extends above the platen and is supported in ears 38 provided upon a paper shelf 39, which usually extends upwardly from the delivery side of the platen. These arms 36 are preferably adjustable along said rod to accommodate different widths of record- 115 120 125 130

sheets, or different positions of the same lengthwise of the platen. To permit the rolls to be released from the platen, the arms at the rear ends are pivoted at 40 upon 5 mounts 41 which slide upon the rod 37 and are splined thereto. Springs 42 connect the arms with the mounts, so that the rolls may always bear as firmly as required against the platen.

10 For releasing the rolls 35, there is provided a special release key 43 upon the end of an arm 44, which is mounted upon a horizontal rock-shaft 45 which extends along the paper shelf 39 and is mounted in the 15 ears 38. Upon this shaft 45 are splined releasing cams 46 which engage the roll-carrying arms 36 to lift the same upon the operation of the release key 43; the parts being so formed that the roll-carrying arms will 20 be locked in released positions, as at Figure 3, by the arm 44 which is arrested by a stop 43^a on the ear 38. Upon lifting the key, the springs 42 will restore the rolls 35 to engagement with the platen 14. The releasing cams 46 are forked at 47 to engage 25 the arms 36, so as to be carried along thereby when the arms are adjusted along the rod 37, and hence the release key 43 will serve to release the rolls wherever the arms are 30 adjusted along the platen.

Variations may be resorted to within the scope of the invention, and portions of the improvements may be used without others.

Having thus described my invention, I 35 claim:

1. In a typewriting machine, the combination with a platen and a platen-frame which is displaceable on the carriage to release the work-piece, of means to clamp an 40 additional work-sheet on the platen, a work-support or paper-shelf forming a part of the platen-frame at the delivery side of the platen, and spring-controlled roll-carrying arms mounted on the back of said paper-shelf for adjustment longitudinally of the 45 platen and swingable away from the platen, said arms extending over the top of the paper-shelf and downwardly thereover to the platen to engage the latter

50 2. In a typewriting machine, the combination with a platen and a platen-frame which is displaceable on the carriage, of a work-support or paper-shelf forming a part of the platen-frame at the delivery side of the platen, a rod mounted on the back of the 55 paper-shelf extending along its top, and spring-controlled roll-carrying arms mounted on said rod for adjustment longitudinally of the platen and swingable away from the platen, said arms extending over the top of the 60 paper-shelf and downwardly thereover to the platen to engage the latter near the printing line.

65 3. In a typewriting machine, the combination with a platen and a platen-frame

which is displaceable on the carriage, of a paper-shelf forming a rigid transverse part of the platen-frame at the delivery side of the platen, a rod mounted on the back of the paper-shelf extending along its top, mounts 70 splined on said rod and longitudinally adjustable thereon, arms pivoted on said mounts, and springs connecting the mounts with the arms which are swingable away from the platen, said arms extending over 75 the top of the paper-shelf and downwardly thereover to the platen to engage the latter under the pressure of said springs.

4. In a typewriting machine having a platen and a paper shelf at the delivery 80 side thereof, the combination of a rod at the rear of the paper shelf, mounts, slideable along said rod and splined thereto, spring-pressed arms pivoted upon said mounts and extending forwardly over said paper shelf, 85 and carrying at their forward ends rolls to run upon the platen, means to release said arms simultaneously from the platen and mechanically lock them in released positions, a second rod, a release key connected 90 to said second rod, cams splined to said second rod for releasing said arms, and means connecting said cams to said arms to be adjustable therewith.

5. The combination with a paper shelf at the delivery side of the platen, of arms extending downwardly over said paper shelf and having at their bottom ends rolls to turn upon the platen, a rod extending along said paper shelf at its upper end, said arms 100 adjustable along said rod and supported thereby, a second rod, a release key connected to said second rod, cams splined to said second rod for releasing said arms, and means connecting said cams to said arms to 105 be adjustable therewith.

6. The combination of a platen, a rod extending along the platen, arms on said rod and adjustable therewith and having means to press the work against the platen, a second rod, a release key connected to said second rod, cams splined to said second rod for releasing said arms, and means connecting said cams to said arms to be adjustable therewith.

7. In a typewriter, the combination with a platen and a platen-frame which is mounted on the carriage to displace the platen, of a paper-shelf forming part of the platen-frame and extending upwardly from the platen on the delivery side of same, a transverse rod mounted at the rear of the paper-shelf near the top, roll-carrying arms supported on said rod by means of horizontally-shiftable mounts to which the arms are pivoted and connected by springs, an arm-releasing rock-shaft also mounted at the rear of said shelf above said rod, said arms curving from said mounts around the rock-shaft and downwardly straight over the shelf to 130

press against the platen, and adjustable means on said rock-shaft engaging the curved parts of the arms to release said arms simultaneously from the platen and to lock them in released positions.

8. In a typewriter, the combination with a platen and a platen-frame, of a paper-shelf forming part of the platen-frame and extending upwardly from the platen on the 10 delivery side of same, a transverse rod mounted at the rear of the paper-shelf near the top, roll-carrying arms supported on said rod by means of horizontally-shiftable mounts to which the arms are pivoted and 15 connected by springs, a rock-shaft also

mounted at the rear of said paper-shelf above said rod, said arms curving from said mounts around the rock-shaft over the top of the shelf and downwardly over the shelf to press against the platen, and cams 20 on said rock-shaft engaging said curved parts of the arms and adjustable together with the latter, to lift said arms simultaneously from the platen and lock them in the lifted positions.

JESSE A. B. SMITH.
